UNITED STATES PATENT OFFICE.

MAX SARFERT, OF PHILADELPHIA, PENNSYLVANIA.

PROCESS OF TREATING HOSIERY.

SPECIFICATION forming part of Letters Patent No. 667,142, dated January 29, 1901.

Original application filed March 13, 1900, Serial No. 8,489. Divided and this application filed October 12, 1900. Serial No. 32,831.
(No specimens.)

To all whom it may concern:

Be it known that I, MAX SARFERT, a citizen of the United States, residing in the city and county of Philadelphia, in the State of Pennsylvania, have invented a new and useful Improvement in Processes of Treating Hosiery, which improvement is fully set forth in the following specification.

My invention consists of a process for treating hosiery for the purpose of removing the nap or lint from the surface thereof to produce what is known as a "silk" or "lisle" finish, this application being a division of my application for patent for a process for giving a silk or lisle finish to hosiery or knit goods filed March 13, 1900, Serial No. 8,489, and I do not therefore claim in this application the process described and claimed therein.

I have found that the nap or lint on the surface of a stocking—for instance, a cotton stocking—can be removed most effectually if the stocking is stretched or distended so that the threads are spread apart. In this way the flames or other singeing medium employed can reach substantially every fiber that forms this nap or lint, it being apparent that when the stocking is in its normal or unstretched state the flame or other singeing medium cannot reach all of these fibers forming the nap or lint.

In carrying out my process I stretch the stocking over a board or former of the kind familiar to those skilled in the art of dyeing which serves to stretch or distend the stocking, so that its threads are spread or separated or pulled apart. The stocking thus stretched or distended on the board or former is passed through the singeing-machine and the fibers forming the nap or lint are removed by the singeing operation. In my said application for a patent for a process for treating hosiery I have set forth the manner in which this singeing process can be most effectually accomplished and which consists in treating hosiery before singeing so that the nap or lint can be more effectually removed when the stocking is singed—for instance, by first saturating the stocking when white or in its natural condition in a solution consisting of the following ingredients—namely, chlorid

of soda or chlorid of potash, one pound; blue stone, one-half pound; anilin salt or anilin oil, four or five pounds. Said solution is known as an "anilin-black" solution and is the first step in the process of dyeing goods fast black. After thorough saturation the goods are dried in the atmosphere and are then in an oxidized state. It is while they are in this oxidized state that their threads are distended or pulled apart by being stretched upon a board or former and passed through the singeing-machine to remove the nap or lint, it being noticed that the board or former acts as a backing for temporarily and conveniently handling a stocking while being subjected to the singeing action and readily removing it therefrom. After the stockings are thus singed they are finished, the finisher or finishing agent being, for instance, chrome of soda or chrome of potash, this being the concluding step in a process of dyeing goods fast black.

Having thus described my invention, what I claim as new, and desire to secure by Letters Patent, is—

1. The herein-described process for treating a stocking, which consists in stretching or distending said stocking, whereby the threads are separated or pulled apart, and then singeing the same.

2. The herein-described process for treating hosiery, which consists in stretching hosiery over a former, whereby the threads thereof are separated or distended, and then singeing said hosiery.

3. The herein-described process for treating hosiery which consists in initially distending the hosiery and then singeing the same.

4. The herein-described process for treating hosiery which consists in initially distending the hosiery laterally and then singeing the same.

5. The herein-described process for treating hosiery which consists in stretching the same on a former, whereby said hosiery is retained in substantially a right line during the act of singeing, and then singeing the same.

6. The method of treating hosiery, which consists in stretching the same on a former,

and then singeing it on its surface and between the stitches thereof, while in a stretched condition and held on said former as a backing.

7. The herein-described process for treating hosiery which consists in singeing the same while the fabric is abnormally stretched or distended in every direction.

8. The herein-described process for treating hosiery which consists in primarily distending the fabric in every direction, whereby substantially every fiber forming the nap or lint can be reached by a singeing agent, and next singeing said hosiery.

9. The herein-described process of treating hosiery which consists in abnormally stretching the fabric in every direction, whereby

substantially every portion of the fiber forming the nap or lint can be reached by a singeing agent, next singeing said hosiery, and lastly allowing the hosiery to assume its normal or unstretched condition.

10. The method of singeing a stocking, which consists in supporting and stretching or distending said stocking from within, with its outer surface exposed, and then subjecting said surface in such condition to a singeing agent.

MAX SARFERT.
